(57) CLAIM

The ornamental design for a pocketed swim suit, as shown and described.

DESCRIPTION

FIG. 1 is a front perspective view of a pocketed swim suit; FIG. 2 is a front elevation view thereof; FIG. 3 is a rear elevation view thereof; FIG. 4 is a left side elevation view thereof; FIG. 5 is a right side elevation view thereof; FIG. 6 is top plan view thereof; FIG. 7 is a bottom plan view thereof; and, FIG. 8 is a front elevation view thereof, shown in use. The broken lines in FIG. 16 showing the pocketed swim suit in use illustrate environment that forms no part of the claim.
